(57) **CLAIM**

The ornamental design for a reel seat for fishing rod, as shown and described.

DESCRIPTION

FIG. 1 is a top perspective view of the reel seat for fishing rod according to the present invention;

FIG. 2 is a bottom perspective view thereof;

FIG. 3 is a side view thereof;

FIG. 4 is another side view thereof, opposite the side in FIG. 3;

FIG. 5 is an end view thereof;

FIG. 6 is another end view thereof, opposite the end view in FIG. 5;

FIG. 7 is a top view thereof;

FIG. 8 is a bottom view thereof; and,

FIG. 9 is a cross-sectional view thereof, taken along line 9—9 in FIG. 7.
